DESIGN FOR A BULL'S-EYE TARGET GAME DEVICE

Irving James Hawkins and Roy L. Nadeau,
St. Paul, Minn.

Application January 23, 1939, Serial No. 82,544

Term of patent 3½ years

To all whom it may concern:

Be it known that we, Irving James Hawkins and Roy L. Nadeau, citizens of the United States, residing at St. Paul, in the county of Ramsey and State of Minnesota, have invented a new, original, and ornamental Design for a Bull's-Eye Target Game Device, of which the following is a specification, reference being had to the accompanying drawing, forming part thereof.

Fig. 1 is a front elevational view of a bull's-eye target game device, showing our new design; and

Fig. 2 is a side elevational view of the bull's-eye target game device.

The rear portion of the device is enclosed and plain.

The entire front is in a single plane. The diamond shape and circular shape representations indicate surface decoration.

We claim:

The ornamental design for a bull's-eye target game device, as shown and described.

IRVING JAMES HAWKINS.
ROY L. NADEAU.
